UNITED STATES PATENT OFFICE.

ABIA ZELLAR BODA, OF COLUMBUS, OHIO.

ELECTRIC RAILWAY-SIGNAL.

SPECIFICATION forming part of Letters Patent No. 397,270, dated February 5, 1889.

Application filed August 22, 1888. Serial No. 283,481. (No model.)

To all whom it may concern:

Be it known that I, ABIA ZELLAR BODA, a citizen of the United States, residing at Columbus, in the county of Franklin and State 5 of Ohio, have invented certain new and useful Improvements in Electric Railway-Signals; and I do hereby declare the following to be a full, clear, and exact description of the invention, such as will enable others skilled in the 10 art to which it appertains to make and use the same.

My invention relates generally to that class of railway-signals of which the block-signals now in use are one type; and it is the purpose 15 of my invention to equip a line of railway of any length with a series of similar signals having electric action and arranged along the line at suitable intervals, said signals being electrically connected with contact-points, 20 which are so placed at or near each signal station or point that they shall successively have electrical connection with contact-arms carried by the locomotive or other part of the moving train, whereby the passage of a train 25 shall set the signals in both directions over a predetermined interval and in such manner that should a second and following train reach any given signal-station before the preceding train has passed the station or point in advance thereof an audible alarm will be given 30 upon the cab of the following train and the engineer notified of the fact that both trains are running within the same interval.

Generally the systems of railway-signals 35 heretofore and now in use for the prevention of collisions of trains are dependent upon the operation of some kind of visible signal, requiring the attention of the engineer to detect whether the signal is set to "danger" or 40 "safety" position. However perfect the operations of these visible signals may be, frequent collisions of trains occur because the engineers may, at the moment of nearing or passing a signal-station be engaged in attention 45 to the machinery of their engines and thus fail to notice whether the signal is in "danger" or "safety" position; or if the trains be running in dark, foggy, or stormy nights the signals may not be at all discernible; also, 50 the duties of engineers, requiring alertness of attention or prompt action, are sufficiently

onerous and responsible without imposing upon them the extra task of watching signal points and stations in order to ascertain whether or not they may safely proceed with 55 their trains.

It is the main purpose of my invention to relieve engineers from the attention and responsibility of detecting the positions of visible signals by placing in the cabs of engines 60 audible alarms which will automatically give warning that trains are in proximity of danger. When a line of railway is equipped with my invention, the engineers will not be required to give any attention to visible signals 65 arranged along said line of railway, as the operation of my audible danger-alarm is entirely automatic and gives notice to engineers of danger regardless of their attention to side posts, lights, or other visible signals. 70

Another distinctive improvement in my invention over the old systems of railway-signals consists in the simplicity of its mechanical parts, which results from the employment of an audible alarm on the moving train, 75 whereas the old systems, with visible signals, are necessarily complicated and expensive, because the signals generally consist of arms or lanterns which must change from "safety" to "danger" position, and, moreover, require 80 greater or less mechanical force, supplied by springs, weights, or compressed air, to operate them. In my invention a slight movement of a series of contact-armatures operated by energized electro-magnets not only become the 85 functional equivalents of but are safer, less complicated, and less expensive than visible signals; also, they bring into operation the audible alarms on moving trains when danger exists in advance of their course of travel, 90 said alarms continuing to sound until the engineers stop their trains or cut the alarms out of circuit.

It is also the purpose of my invention to so arrange the system of signals that the same or 95 a similar notification shall be given to the engineer of trains running in the same or in opposite directions, whereby danger of collision upon a single track shall be wholly avoided, the approach of trains within a predetermined 100 interval being instantly indicated to the engineers of such trains without regard to the

relative direction of movement or travel of such trains.

My invention also comprises an audible alarm, which is carried by a locomotive or other part of a train and operated by a local battery, which is also arranged upon a convenient part of said engine or train, the circuit of said battery being established at any signal station or point by the arrangement of 5 signals which was produced at said point by the passage of a preceding train, and which will remain until the said train has passed the next signal station or point and thereby restored said signals at the rearward stations to 10 normal position; and at the same time it will set those at the advance stations to what may be termed the "danger" position, provision being made upon single-track lines for operating the signals upon both sides of the line simultaneously and from either side of the locomotive, whereby the presence of two trains upon the same or upon adjacent intervals is indicated whether said trains are moving in 15 the same or in opposite directions. It is my purpose, in short, to provide a simple and reliable system of electrical signals which are adapted for use upon any line, whereby the approach of trains within a predetermined interval of each other shall be instantly indicated to the engineers by an audible alarm, which will operate until checked.

To these ends my invention consists in the several novel features of construction and arrangements or combinations of parts which 20 are hereinafter fully disclosed in the description, drawings, and claims.

Referring to the accompanying drawings, forming part of this application, wherein the same reference numerals and letters indicate 25 the same or corresponding parts, Figure 1 represents a diagram showing the arrangement of signals and circuits at two adjacent stations or points, a railway-track, a terminal station of the road, and an engine about to pass between said signal-stations; Fig. 2, a 30 partial diagram showing the relative change produced by the passage of a train by a signal station or point on the line of a road; Fig. 3, a detail section and partial plan view 35 of one of the signal-posts and its contact points and connections, and Fig. 4 a detail view showing a slight modification of construction hereinafter described.

In the drawings the reference-numeral 1 denotes a roadway, which may be either a 40 double or single line of tracks, though for convenience of illustration I have shown the latter only. Along this line of road I arrange a series of signal stations or points, which 45 are separated by distances or intervals of any suitable length—as, for example, one, two, or three miles. Inasmuch as the construction and arrangement of parts at each signal point or station is substantially the same, I have 50 only shown two of such stations and their proper equipments.

The reference-numeral 2 designates one of

the terminal points of the road, or it may serve to denote a station located between any two signal-stations. From this terminal or other station extends a line-wire, 3, which is carried beside the roadway upon any suitable insulated supports—such as the telegraph-poles in use—and connected up in each signal-station in the manner hereinafter described. 75

At each signal-station along the line of road is placed what may, for convenience, be termed a "signal-post," which is illustrated in detail in Fig. 3. The construction of this, however, may be greatly modified without affecting the nature of my invention, the form shown in the drawings being only typical. Each signal-post may consist of a body or upright portion, 4, upon which a bridge or plate, 5, of non-conducting material, is hinged or 80 pivotally mounted at 5' and normally drawn down by a spring, 6, into a position slightly inclined from the horizontal. Upon this bridge or plate 5, on its under side, is mounted a bracket, 7, made of suitable conducting material and provided with a binding-screw, 8. This bracket is held by the tension of the spring 6 in electrical contact with an adjustable post, 9, carried by a conducting-plate, 10, which is mounted upon the side of the upright portion 4 of the signal-post and provided with a binding-post, 12. The line-wire 3 is connected to a binding-post, 13, which has connection by a wire, 14, with said bracket 7. 100

Upon the pivotally-mounted bridge or plate 5 are arranged three electrical contact-points, 15, 16, and 17, which are arranged in substantial parallelism with the roadway and separated from each other by suitable intervals; 105 also, upon the same bridge or plate are placed two other contact-points, 18 and 19, which lie in a separate but substantially parallel line and alternate with said contact-points 15, 16, and 17 in the manner most plainly shown in 110 Fig. 3 of the drawings. The contact-point 15 is electrically connected to the bracket 7 by a wire, 20, the contact-point 16 is connected by wire 21 with a binding-post, 22, and contact-point 17 is similarly connected by a wire, 23, to a binding-post, 24. Of the separate and 115 alternating series of contact-points 18 and 19 the former, 18, is connected by a wire, 25, to a binding-post, 26, on the upright 4 of the signal-post, while the latter, 19, is connected in 120 a similar manner by a wire, 27, to a binding-post, 28, which is connected by a wire, 29, with a similar binding-post on the opposite side of the track, which is constructed and arranged the same as that shown in Fig. 3. 125

It is deemed best to first describe the equipment of a single signal-station, then the electrical connections with the signal-posts at said station, and then the operation of the signaling mechanism in connection with passing 130 trains.

Referring to Fig. 1 of the drawings, the reference-letter S designates any suitable support or signal-board, composed of wood or

similar insulating material. Upon this support are arranged electro-magnets 30 and 30' and an armature-lever, 31, one end of which, 32, is insulated in any suitable manner; also, 5 upon the ends of this armature-lever are mounted insulating-blocks of rubber, 33 and 34, and upon suitable uprights or brackets, 35, are secured contact-arms 36 and 37, which have elastic or yielding bearing upon the ends 10 of said armature-lever and are alternately cut out of circuit as the latter vibrates; also, upon said support or signal-board S are arranged similar electro-magnets, 38 and 38', which attract the ends of an armature-lever, 39, which 15 is provided with an insulating rubber block, 40, upon one end; also, an elastic or yielding contact-arm, 41, mounted on an upright bracket, 42, engages with the end of this armature-lever. A third set of magnets, 43 and 20 43', is also arranged upon said support or signal-board and attracts an armature-lever, 44. Upon the end of said lever which is attracted by magnet 43 is mounted an insulating-block, 45; also, upon an upright or bracket, 25 46, is arranged an elastic or yielding contact-arm, 47, which rests upon this armature-lever.

The parts thus described are electrically connected as follows: The two stations illustrated, as well as all others upon the road, are 30 connected by the line-wire 3, which, as more plainly shown in Fig. 3, is in normal connection through binding-post 13, wire 14, bracket 7, and wire 20 with contact-point 15 on the bridge or plate 5. Line-wire 3 is also in connection through contact-point 9, binding-post 35 12, and wire 12' with binding-post 49 and the coil of magnet 30, as shown in Figs. 1 and 2. The contact-point 16 is connected by wire 21, binding-post 22, wire 48, and binding-post 49 40 with magnet 30; also, binding-post 49 and magnet 30 are connected by a wire, 50, through binding-post 51 and wire 52, to armature-lever 31, a ground-connection being made through wire 53. From binding-post 51 the connection 45 is made by a wire, 54, carried to binding-post 55, thence through magnet 38, binding-post 56, and by wire 57 to line-wire 3 and the station beyond. The contact-point 17 is connected by wire 23, binding-post 24, and wire 59 to binding-post 60. From this point the 50 connection is by way of the magnet 43', binding-post 61, and wire 62 to earth. The contact-point 18 in the separate and alternating series upon the bridge 5 is connected by wire 55 25 to binding-post 26, thence by wire 63 to binding-post 64, and by wire 65 to the end of armature-lever 44. From this point connection is by way of armature-lever 44, contact-point 47, and wire 66 to the earth. All the 60 ground-connections are made through the point 67.

Referring now to the opposite side of the track, a series of signals is here arranged precisely the same as those already described, 65 with the single difference that, being arranged for trains moving in the opposite direction, they have a reverse order, or the arrangement

that would be produced by simply turning the signal-board S end for end. A signal-post, 4, is also provided on this side of the 70 track and connected up in the manner already set forth, but having the free end of its bridge or plate 5 turned in the direction of movement or travel of the trains, by which the controlling impulses are transmitted through 75 the contact-points of the automatic bridge. These signal-posts and the signals with which they are connected are arranged upon opposite sides of the track at each signal station or point, and their pivotally-mounted bridges 80 or plates are turned in opposite directions, one being acted upon by trains moving in one direction and the other by trains moving in the opposite direction.

From the final contact-point, 19, in the separate and alternating series thereof, which are secured upon the bridge 5, a wire, 27, connects, by way of binding-post 28 and wire 69, (which latter passes across the track, either above or below the same,) with the binding-post 71, which connects with the insulated end 32 of the armature-lever 31 on the signal-board S' by a wire, 72. In this set of signals the several connections are the same as those already described, and the parts are designated by similar characters. From the contact-point 19 on this signal-post, arranged as described, a wire, 70, is led through a suitable binding-post across the track to a binding-post, 71, on the support or signal-board S. 95 This post also connects by a wire, 72, with the insulated end 32 of an armature-lever, 31. The remaining electric connections will be indicated in the course of the description.

Upon the locomotive, within the cab, or in any suitable position upon the train I arrange a battery, B, from one pole of which the current is grounded through the running-gear in the usual manner. Connected with the other pole of the battery is a wire, 74, passing through the electro-magnet 75 of a bell, 75', or other audible signal, from which said wire passes to the coil of a magnet, 76, which, when energized, attracts an armature-lever, 77. The end of this armature-lever vibrates between the contact-points 78 and 79, the former being connected by wire 80 to one pole of the battery B.

A support, 81, is movably secured to a transverse bar, 81', which is mounted upon the engine or other suitable part of the train in such manner that said support may be laterally adjusted thereon and secured in place by a bolt or screw, 81''. To each side of this support are secured conducting-arms 82 and 82', 120 which project outwardly over the position occupied by the signal-posts. These arms are of different relative lengths, and their arrangement is such that, when adjusted, their ends will pass over the signal-posts in the vertical planes of the two series of contact-points 15, 16, and 17 and 18 and 19. Upon the outer extremities of these arms are mounted rolling contact disks or wheels 83, of conducting ma-

terial. I preferably mount the inner ends of said arms 82 and 82' upon hinged or yielding brackets 84, so as to enable them to act with a yielding pressure upon said contact-points 5 when passing over the same. From the contact-point 79 two wires, 85 and 86, are carried to the two shorter arms 82', and in a similar manner two wires, 87 and 88, are carried from the wire 74, leading from one pole of the battery to the two longer arms, 82. The alarm carried upon the train may consist of any ordinary electric call-bell.

Let it be supposed that the locomotive or train equipped in the manner just set forth 15 leaves the terminal station 2 of a line of railway. At this station are arranged two contact-points, 87' and 88', which are separated by a slight interval and both placed in electrical connection with the line-wire 3. When the 20 wheeled-arm 82 makes electrical contact with the point 87', as the train leaves said station an impulse will be sent over the line-wire 3 from the battery B, and this impulse will pass over said line-wire to the binding-post 13 on 25 the signal-post 4 of station No. 1; thence the impulse will pass by wire 14, bracket 7, post 9, plate 10, binding-post 12, wire 12', and binding-post 49 to the coil of magnet 30; thence by binding-post 30'', wire 50, binding- 30 post 51, and wire 52 to armature-lever 31, and thence by contact-point 36 and wire 53 to the ground. This energizes magnet 30, attracts the armature-lever 31, cuts off the ground-connection by way of contact-point 36 and 35 wire 53 and brings the insulated end 32 of said armature-lever and its attached wire 72 in connection with the ground through contact-plate 37 and wire 53. The second impulse imparted through contact-point 88' be- 40 ing then made, the current is passed from the battery on the engine or other part of the train through the wheeled arm 82 over line-wire 3 to the first signal-post, where it passes by the course already described to the bind- 45 ing-post 49 and magnets 30; thence by binding-post 30'', wire 50, binding-post 51, wire 54, and binding-post 55 to magnet 38; thence by way of binding-post 56 and wire 57 to binding-post 58; thence by line-wire 3 to the 50 next station or signal-point beyond, where it enters the binding-screw 13 of said signal-post, traverses wire 14, bracket 7, post 9, binding-post 12, and the wire 12', leading to magnet 30 at said station, and thence to 55 ground by the course already set forth, attracting the armature-lever 31 at the second station ahead and bringing its insulated end 32 into ground-connection in the manner already described in connection with the pre- 60 ceding station. Let it next be supposed that the engine and train after leaving the terminal station, and having set the signals in the manner described, have reached signal station or point No. 1, where the wheeled con- 65 ducting-arms 82 and 82' encounter the bridge or plate 5 and have rolling contact thereon, the arm 82 passing its wheel 83 over the three

contact-points 15, 16, and 17, while the conducting-arm 82' passes over the separate and alternating contact-points 18 and 19. As the 70 longer wheeled conducting-arm, 82, strikes the contact-point 15, an impulse is sent back over the line-wire 3, and the connection between bracket 7 and post 9 is broken by reason of said conducting-arm tilting the bridge 5 upon 75 its pivot 5' against the tension of the spring 6. The action produced by this impulse will be described hereinafter. As said conducting-arm next strikes the contact-point 16, an impulse is sent over wire 21 and through binding- 80 post 22, thence by wire 48 to binding-post 49, magnet 30, wire 50, binding-post 51, wire 54, binding-post 55, magnet 38, binding-post 56, wire 57, binding-post 58, and line-wire 3 to the automatic or pivoted bridge 5 at the next 85 station in advance, when said impulse is transmitted in a similar manner to the second station in advance, attracting the armature-lever 31 at that station and bringing its insulated end 32 into ground-connection through the 90 contact-arm 37 and wire 53. As the conducting-arm 82 makes contact with the final one, 17, of the three contact-points, an impulse is transmitted over wire 23, through binding-post 24 and wire 59, to the binding-post 60, and 95 thence passes through magnet 43', which attracts the armature-lever 44, the current grounding through the binding-post 61 and wire 62. When the armature-lever 44 is thus thrown into the position shown in Fig. 2, its 100 end is in connection with the earth through the contact-arm 47, bracket 46, and wire 66, thereby giving a direct earth-connection to the final contact-point, 17. The signals will now remain in this position until the next 105 succeeding signal-station is reached by the train, whereupon the following result will ensue: When the wheeled conducting-arm 82 makes contact at station No. 2 with the bridge 5, the connection between post 9 and bracket 110 7 being broken, an impulse will be sent from contact-point 15 back over wire 12' and line-wire 3 to station 1, when the current will enter at binding-post 58 and pass through contact-point 41, armature-lever 39, and wire 53 to 115 binding-post 54; thence through magnet 38', attracting armature-lever 39 back to normal position, as shown in Fig. 1; thence by binding-post 55 and wire 55' to binding-post 57'; thence through magnet 43, attracting armature-lever 44, and back to its normal position, 120 breaking the ground-connection through wire 66 and its connections; thence through binding-posts 58' and 58'' by way of a wire, 58'', back to the magnet 30', attracting armature-lever 31 to its normal position, and to ground through binding-post 30''' and wire 34'. This will be the action of the signals so 125 long as the railway sections or divisions are not invaded by other trains during the period 130 of time occupied by any given train in passing from point to point or station to station. Should it happen, however, that after leaving station No. 1, and before arriving at

station No. 2, a second and following train should also arrive at and pass signal-station No. 1, then the result will be as follows: The respective parts being in the position shown 5 in Fig. 2 of the drawings, the wheeled conducting-arm 82', in making contact with the first, 18, of the alternating series of contact-points, will form a perfect ground-connection through said arm by way of the wire 25, binding-post 26, wire 63, binding-post 64, wire 65, armature-lever 44, contact-arm 47, and wire 66. The said contact-point 18 being under these circumstances in ground connection, the circuit will be from one pole of battery B 10 by wire 74 through call-bell coil 75, thence to the coil of magnet 76, energizing the same and attracting the armature-lever 77 and closing the connection between said lever and contact-point 78, and thence back to the other 15 pole of the battery through wire 80. The complete circuit, prior to the connection, will be through contact 79 and thence by wire 85 to wheeled arm 82'. The moment, however, that the armature-lever 77 is operated the circuit 20 will be from the battery B through wire 74, the call-bell coil 75, magnet 76, armature-lever 77, contact-point 78, and wire 80 to the other pole of the battery, which may thus be said to be switched in, whereby the call will 25 continue to act until it is checked by the engineer. The latter is thus notified that his train is within undue proximity to the preceding train and knows that the latter is still upon the section or interval separating 30 the stations.

It will be readily seen from the foregoing description that by the duplicate arrangement of parts upon opposite sides of the track each train will receive an alarm from approaching trains moving in the opposite directions. For example, an approaching train will, at a distance of two signal-stations, set the armature-lever 31 on the signal-board S' to ground. Then as the engine shown in the drawings reaches either of the two stations in advance of the approaching train the wheeled conducting-arm 82' will complete the circuit of the call-bell through the contact-point 19 on the bridge or plate 5 and cause the current to pass thence by wire 69, binding-post 71, wire 72, insulated end 32 of armature-lever 31, contact-arm 37, and wire 53 to earth. Should no train be within the distance or interval named, then there will be no action, as 55 the current cannot get to earth and thereby switch in the call-bell circuit.

It will be obvious from the foregoing that my invention provides a simple and reliable system of signaling, which is operated wholly 60 by a battery carried by the locomotive or other part of the moving train, whereby all the signals are set for two signal stations or points in advance of the moving train in such position as to insure an alarm in the event of 65 a train approaching in the opposite direction, said signals being left in the positions to which they are set till they are restored to

normal position by the passage of the train by the next ensuing station. It should be particularly noted, however, that while every 70 train sets the signals for two stations in advance of its own position it only restores the signals to normal position at the station last passed by said train. The reason for this is obvious, as a train having movement in one 75 direction might arrive at a given signal-point at the same instant that an oppositely-moving train reached the station in front of it, whereupon the action of the one would neutralize that of the other. By setting these 80 signals for two stations ahead of each train, however, such a contingency is wholly avoided, and in the case of a following train no similar result is to be apprehended.

The support 81, as already stated, is rendered adjustable laterally in order to bring the wheeled arms 82 and 82' over the signal-posts on either side of the roadway, since in backing up it is as important to operate the signals as in moving in the opposite direction. 90 I may also mount these wheeled conducting-arms and the bridges or plates 5 and their contact-points beneath the engine or other part of the train, as shown in Fig. 4, and so arrange them that they will make the necessary contacts between the rails. An elastic bearing may also be provided for said wheeled conducting-arms in order to insure yielding contact with said bridges or plates.

Having thus fully described the construction, arrangement, and operation of the several parts of my invention, what I claim as new is—

1. A series of electric-railway-signal stations arranged upon both sides of a railway and at 105 suitable distances apart, in combination with two independent series of contact-points at said stations, a main-line wire, a moving train, an audible alarm, conducting-arms, and a battery located on said moving train, an electro-magnet in circuit with said battery, an armature-lever and contact-points in circuit therewith and with said battery, and an armature-lever located on said moving train, whereby an 110 audible alarm may be sounded thereon, substantially as described.

2. In an electric signal, the combination, with a series of electro-magnets, their armature-levers, a main-line wire and suitable ground-connections, of a signal-post provided 120 with two separate series of contact-points connected to said line-wire, a reversely-arranged system of signals, a battery mounted upon a moving train, an audible alarm connected with one pole of said battery, a switch-lever, and 125 conducting-arms extending from said moving train and electrically connected with one pole of said battery, and a contact-point intermediate of said switch-lever and conducting-arms, substantially as described.

3. In an electric railway-signal, the combination, with a duplicate reversely-arranged system of signals, of a signal-post provided 130 with a pivotally-mounted bridge or plate car-

rying a double series of independent alternating contact-points, a spring normally holding said bridge in an inclined position, a main-line wire, two contact-points connected therewith, and a battery and conducting-arms mounted upon a moving train, whereby electrical impulses are sent over said main line to the signals, substantially as described.

4. In a system of electric signals, the combination, with a series of electric circuits, of a signal-post having a pivotally-mounted bridge provided with contact-points, connecting-wires leading to the respective circuits, a bracket connected to said bridge, a main-line wire, and a spring which normally draws said bridge into inclined position for making electrical contact between said bracket and a wire leading to one of said signal-circuits, substantially as described.

5. An electric railway-signal consisting of two contact-points, 87' 88', a main-line wire, 3, which is electrically connected therewith, an electro-magnet, 30, which is normally in circuit with said line-wire, an armature-lever, 31, in the same circuit, and a wire, 53; leading to the earth, in combination with a conducting-arm, 82, and a suitable battery on a moving train, whereby said armature-lever is operated to shunt the circuit transmitted to it from said battery when said conducting-arm comes in contact with said contact-points, substantially as described.

6. The combination, in an electric signal, of an electro-magnet, 30, a contact-point, 15, and wires connecting said point with the coil of said magnet, an armature-lever, 31, which is normally in circuit with said magnet and the earth, an electro-magnet, 38, and wires connecting the same with said magnet 30, the line-wire 3, connecting with the signals of another station, and a conducting-arm, 82, and a battery, B, mounted upon a moving train, whereby the signals of the stations are simultaneously set, substantially as described.

7. The combination, in an electric signal, of 45 a contact-point, 16, an electro-magnet, 30, and wires connecting the coil thereof with said contact-point, an armature-lever, 31, which is normally in circuit with said magnet and the ground and provided with an insulated end, 50 32, a connecting-wire, 72 and 70, a contact-point, 19, on the opposite side of the track, a moving train, the conducting-arms 82 and 82', and the battery B and the connections mounted on said train, substantially as and for the purpose described.

8. The combination, in an electric signal, of a contact-point, 17, an electro-magnet, 43', connecting therewith by suitable conducting-wires, an armature-lever, 44, operated by said magnet, a contact-point, 47, connecting-wires 60 63 66, extending therefrom to ground, contact-point 18, conducting-arms 82 82', battery B, alarm 75', alarm-magnet 75, magnet 76, armature-lever 77, contact-points 78 79, and 65 their electric connections, whereby an alarm is sounded upon a moving train, substantially as described.

9. The combination, in an electric signal, of the pivoted bridge 5, the post 4, the bracket 70 7, the contact-point 15, the connecting-wire 12', and line-wire 3 with the binding-post 58, contact-point 41, armature-lever 39, wire 53, electro-magnet 38', wire 55', electro-magnet 43, wire 58'', electro-magnet 30', wire 34', leading to the earth, a moving train, and the conducting-arms 82 82', and the battery B, carried by said train, whereby the signals are returned to normal position, substantially as 75 80 described.

In testimony whereof I affix my signature in presence of two witnesses.

ABIA ZELLAR BODA.

Witnesses:

J. B. McDONALD,
I. D. HUNT.
